[57] CLAIM

The ornamental design for an eyeglass frame, as shown and
described.

DESCRIPTION

FIG. 1 is a perspective view of an eyeglass frame showing
my new design;

FIG. 2 is a front view thereof;

FIG. 3 is a rear view thereof;

FIG. 4 is a top view thereof;

FIG. 5 is a bottom view; and,

FIG. 6 a right side view thereof (the left side view is
symmetrical).The broken line showing on the temple and temple tips is for
illustrative purposes only and forms no part of the claimed
design.
